E. W. STEER

BRASSIÈRE

Filed June 3, 1924

Invictor
Emma Wilson Steer
by Seymour Taaffe
at his

UNITED STATES PATENT OFFICE.

EMMA WILSON STEER, OF NEW HAVEN, CONNECTICUT.

BRASSIÈRE.

Application filed June 3, 1924. Serial No. 717,472.

Fig. 1 is a front view, from the left, illustrating my improved brassière as upon the figure.

Fig. 2 represents plan views of the several parts detached.

This invention relates to an improvement in brassières. In the more general construction of brassières, they are formed from a long strip of material, with a substantially straight upper edge, and this edge is sometimes gathered so as to conform to the figure, but this does not produce a smooth-fitting garment, which is desired and necessary, particularly for full figures. The object of this invention is to form a brassière in sections, and so shape the sections as to produce the desired fullness over the bust, and a close fit of the garment to the figure above the bust, and the invention consists in the construction as hereinafter described and particularly recited in the claims.

In carrying out my invention, I employ a front 5 having inclined straight side edges 6 and 7 at the upper portion, and reversely inclined straight sides 8 and 9 at the lower portion. Attached to the sides of the front are side-fronts 10 and 11 respectively formed with inclined straight edges 12-13 and 14-15 to be stitched to the side edges 6-8 and 7-9. The upper parts 16-17 of the rear edges of the side-fronts and the lower parts 18-19 of those edges are reversely inclined and are connected with a right side-back 20 and a forward left side-back 21, the forward edges 22-23 and 24-25 of which are reversely inclined and the lower parts 23 and 25 attached to the edges 18 and 19. The side-back 20 is connected to one edge of a back 26, the edge 27 of which is connected to the edge 28 of a left side-back. The edge 27 of the back is connected to the edge 28 of a rear left side-back 29, the edges of the front left side-back 21 and the rear left side-back 29 being respectively provided, one with hooks 30, and the other with eyes 31, by which the ends of the garment may be connected under the left arm. The edges 16 and 22, between the side-front and right side-back, are provided with a series of eyelets 32, and the corresponding edges 17 and 24 of the side-front 11 and front left side-back 21 are provided with eyelets 33 to receive lacings 34, by which those edges may be drawn together to the desired extent.

The garment, when assembled, may be

trimmed in any desired manner, and if desired, provided with shoulder-straps 35.

By thus shaping the front and side-fronts, as well as the rear edges of the side-fronts and the forward edges of the right side-back 69 and front left side-back, fullness is provided over the breast and gives the desired shape so that the upper edge of the garment closely fits the figure of the wearer, thus giving the desired support and covering the person, and 65 additional fitting is secured through the lacings 34.

The position of the angle at the sides of the front and side-fronts will correspond to the figure of the person for whom the garment is desired. By employing straight edges, fullness is provided where desired, and the upper edge is so contracted that the bust is held down.

If desired, the upper edge 36 of the back 75 26 may be curved upward and the lower edge 37 cut away, as may be required, to fit the figure. Hose-supporter straps 38 may be secured to the lower edge of the front 5 at opposite sides, and hose-supporter straps 39 80 may be attached to the lower edge of the back 26 at opposite sides, the length of these straps corresponding to the figure of the wearer.

I claim:

1. A brassière, comprising a front, side-fronts, right side-back and front left side-back, the upper portion of the front having its side edges inclined downward and rearward from the upper edge and the lower portion having its side edges inclined thence downward and inward to the lower edge, the forward edges of the side-fronts correspondingly extending downward and forward from the upper edges and thence downward and rearward to the lower edges, the rear edges of the side-fronts also correspondingly extending downward and rearward from the upper edges and thence downward and forward to the lower edges, the side-backs also 95 correspondingly having their forward edges inclined downward and forward from the upper edges and thence downward and rearward to the lower edges, the adjacent edges of the several parts connected together, 100 whereby is produced a garment having a close fit above the bust and a fullness to receive and inclose the bust.

2. A brassière, comprising a front, side-fronts, right side-back and front left side- 110

back, the side edges of the front inclined downward and rearward from the upper edge and thence downward and inward to the lower edge, the forward edges of the side-fronts 5 extending downward and forward from the upper edges and thence downward and rearward to the lower edges, the rear edges of the side-fronts extending downward and rearward from the upper edges and thence downward 10 and forward to the lower edges, the side-backs having their forward edges inclined downward and forward from the upper edge and thence downward and rear-

ward to the lower edges, the adjacent edges of the front and side-fronts connected together and the lower portions of the side-fronts connected to the side-backs, the upper adjacent edges of the side-fronts and side-backs provided with rows of eyelets, and lacings passing through said eyelets, whereby a fullness is obtained at the front, below the upper edge, and whereby the upper edge may be adjusted. 15 20

In testimony whereof, I have signed this specification.

EMMA WILSON STEER.
